COMBINED TUMBLER AND TOOTHBRUSH HOLDER

Leslie E. Lanczi, 5360 Walkley Ave., Apt. 18,
Montreal, Quebec, Canada

Filed June 21, 1963, Ser. No. 75,464

Term of patent 7 years

(Cl. D4—3)

FIG. 1

The dominant features of my design reside in the portions shown in full lines.

I claim:

The ornamental design for a combined tumbler and toothbrush holder, as shown and described.
